[57] CLAIM

The ornamental design for a humidity and temperature
meter, as shown and described.

DESCRIPTION

FIG. 1 is a front elevation view of a humidity and tem-
perature meter showing my new design;

FIG. 2 is a right side elevational view, the left side

elevational view being a mirror image;

FIG. 3 is a top plan view;

FIG. 4 is a rear elevational view; and

FIG. 5 is a bottom plan view thereof.

FIG. 3

FIG. 5

FIG. 4
